CLAIM

The ornamental design for a pet privy guard, as shown and described.

DESCRIPTION

FIG. 1 is a top, front, right perspective view of a first embodiment of a pet privy guard in accordance with our design;

FIG. 2 is a left, bottom, rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines shown in the drawings depict portions of the pet privy guard that form no part of the claimed design.

1 Claim, 4 Drawing Sheets(56)
